J. H. TAYLOR

DOOR LOCK

Filed June 27, 1923

J. H. Taylor
Inventor

By *C. A. Snoddy*

Attorney

UNITED STATES PATENT OFFICE.

JAMES H. TAYLOR, OF PASADENA, CALIFORNIA.

DOOR LOCK.

Application filed June 27, 1923. Serial No. 343,061.

To all whom it may concern:

Be it known that I, JAMES H. TAYLOR, a citizen of the United States, residing at Pasadena, in the county of Los Angeles and State of California, have invented a new and useful Door Lock, of which the following is a specification:

This invention relates to locks for doors and other closures of the type known as case locks.

The object of the invention is to provide a lock of this character having means for locking the spring projected latch whereby the door is held securely closed until the knob is turned to release the latch and all possibility of rattling is prevented.

Another object is to provide a lock the keeper of which is equipped with cam means for locking the latch in closed position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Figure 1 represents a side elevation of a portion of a door with this improved lock shown applied, the frame of the door being shown in section and the keeper mounted in said frame being partly in elevation and partly in section; and

Fig. 2 represents a sectional view taken on the line 2—2 of Fig. 1.

In the embodiment illustrated a door 1 of ordinary construction is shown in connection with its frame 2 the latter being equipped with a keeper 3 for cooperation with the lock 4 carried by the door. This lock 4 has a spring projected latch 5 which is designed to be retracted by turning of the knob 6 and is also provided with the usual locking bolt 7 controlled by a key not shown.

The frame 2 has a recess 8 formed therein which registers with an opening 9 in the keeper 3 when the latter is applied for reception of the lock bolt 7 as is shown clearly in Fig. 1. The keeper 3 which is in the form of a metal plate has a casting 10 extending laterally from its rear face and housed within the frame 2. This casting 10 has a recess 11 extending from end to end

thereof and closed at one end by a detachable plate 16. The recess 11 is designed to receive the spring latch 5 when the door is closed and opening through the upper and lower walls of the recess are obliquely extending sockets 12 and 13 in which are mounted spring projected balls 14 which normally extend into the path of the latch 5 and are supported by coiled springs 15 which operate to normally project the balls in the path of the latch and which engage the opposed faces of the latch when the door is closed and lock it against opening until the latch is retracted by turning of the knob 6 which causes it to be withdrawn from between the balls against the tension of the springs 15.

To insert the balls and springs in the casting 10 the plate 16 is removed and the balls entered in the bores 12 and 13 and then the springs 15 passed in after them and which operate to project the balls through the open ends of the bores which communicate with the recess 11.

In the use of this device the parts being mounted as shown in Fig. 1, the closing of the door 1 will cause the latch 5 to enter the recess 11 in a direction longitudinally of the recess thereby forcing the balls 14 inwardly into their sockets against the tension of the springs 15 which permits the latch to slide into said recess and immediately it passes into locking position the balls will be forced out by the springs 15 effecting a cam like locking engagement with the latch 5 and thus securely holding the latch against outward movement through the recess 11. The latch 5 is retracted by the turning of the knob 6 which pulls it out through the opening in the side wall of the casting 10 causing the spring pressed balls to roll in their sockets and after the latch passes out the balls are returned ready for the next operation.

It will thus be seen that the door is not only held locked by the engagement with the balls to the latch but it holds the door securely against rattling.

Various changes in the form, shape, proportion and other minor details of construction may be made without departing from the principle or sacrificing any of the advantages of the claimed invention.

I claim:—

1. The combination of a keeper and a lock, one having a socket and the other a

latch, said socket having a bore extending obliquely therefrom and opening thereinto, and a spring projected ball mounted in said bore and adapted to engage the latch when the door is closed to lock the latch in closed position.

2. The combination of a keeper having a recess opening through the front wall thereof and through one side wall, bores extending obliquely from the upper and lower walls of said opening and opening at one end through said walls, spring projected

balls mounted in said bores and adapted to extend into said opening, and a latch adapted to enter said opening between said balls thereby locking it against opening in one direction.

In testimony that I claim the foregoing as my own, I have hereto affixed my signature in the presence of two witnesses.

JAMES H. TAYLOR.
